UNITED STATES PATENT OFFICE.

AUGUSTE JULES ADRIEN BLARINGHEM, OF MAZINGARBE, FRANCE, ASSIGNOR TO
SOCIÉTÉ ANONYME D'ECLAIRAGE ET D'APPLICATIONS ELECTRIQUES, OF ARRAS,
PAS-DE-CALAIS, FRANCE.

EXTRACTION OF KRYPTON AND XENON FROM AIR.

Application filed May 26, 1924, Serial No. 716,065, and in France June 29, 1923.

This invention relates to processes of recovering krypton and xenon, from liquid oxygen containing the same and it comprises a process in which liquefied oxygen is allowed to evaporate and the vapors thereof passed through an absorbent material such as carbon; it further comprises a process in which the absorbent material is kept cold by means of gaseous oxygen.

10 Notwithstanding their relatively high boiling points (respectively -151.8° and -106.9°), krypton and xenon have an appreciable volatility at the temperature of liquid air. This is the chief reason why they can 15 not be obtained as a residue from the evaporation of liquid oxygen.

Thus, after a prolonged operation of an industrial oxygen liquefying apparatus, only a small fraction of the amount of krypton 20 and xenon which have passed through the apparatus is obtained in the residue from the evaporation of the liquid oxygen.

The experiments made by the applicant have shown, in fact, that these gases, krypton 25 and xenon, progressively accumulated in the liquid oxygen in an apparatus working in a prolonged and continuous manner (as is the case of actual industrial apparatus) soon acquire therein an appreciable vapour tension, 30 considering the small quantities present, and gradually increasing in proportion to the admission of the gases. A progressively increasing quantity of these gases, will therefore escape with the oxygen, until there will 35 be an equilibrium established between the quantities which enter and those which escape.

Enlightened by these considerations, instead of recovering krypton and xenon from 40 the residue of liquid oxygen, the present inventor essentially employs for the extraction of krypton and xenon, gaseous oxygen supplied in the course of operation of the apparatus.

45 This method has first the capital advantage that the individual oxygen apparatus can thus be used for the extraction of the said gases, without being modified in their principle, or changed in their operation.

50 The annexed drawing shows, by way of example, the application of the process in an apparatus of the type Claude for the production of oxygen by the liquefaction of air.

In this apparatus, *a* is the reservoir, *b* are the

cylinders of the air compressor, *c* the pipe 55 line of the refrigerator of the compressor, *d* the exchanger, *e* the expansion cylinder, *f* the entrance of the compressed oxygen at critical temperature, *g* the exchanger for the liquid oxygen; *h* is a liquid oxygen reservoir. 60 The reservoir, (*m*), containing the absorbing material is disposed at the outlet of the liquefier, (*k*). It is traversed by the current of the gaseous oxygen; *n* is the pipe line which permits extraction of the krypton and the 65 xenon retained by the absorbing material. Suitable valves are associated with the pipes in order to control the system. This extraction operates naturally after the circulation of the gaseous oxygen in the reservoir 70 is interrupted.

The process is based on the fact that if this oxygen is passed over or through carbon, or similar materials, silica for instance at an intermediate temperature between 75 -182.5° and the surrounding temperature, this carbon, which will be very rapidly saturated with oxygen, will first of all in addition retain krypton and xenon under tensions much lower than their normal tensions 80 at the same temperature. Here again, the tension will gradually increase and the accumulation of these gases will not be capable of exceeding a certain limit, but it will be understood that this limit will depend to a 85 considerable extent on the temperature. Even if the operation is carried out at a temperature in the neighbourhood of -182.5° , the tensions of krypton and xenon can remain indefinitely small and, with a sufficient 90 mass of carbon, the saturation will be reached or even approached only after a very long time, which can exceed the longest practical periods of operation of industrial apparatus. 95

A large portion of krypton and xenon of the air treated can thus be retained and extracted by the fine carbon.

The principle of the method consists therefore in causing the oxygen produced by the 100 oxygen apparatus to pass into a vessel containing a sufficient quantity of carbon or another suitable material and maintained at a suitable temperature so that the equilibrium in krypton and xenon is not reached or even, if possible, approached during the period of operation of the apparatus. 105

Another feature of the present invention

consists in the manner of maintaining the carbon at the low temperature most suitable.

The means forming the subject-matter of this phase of the invention consists in giving to the carbon the temperature of the oxygen and causing the oxygen to contact with the carbon at a suitable temperature. Advantage is taken of the fact that during its passage in the heat exchangers of the oxygen apparatus, the oxygen passes through the entire scale of temperatures comprised between -182.5° and the surrounding temperature.

By utilizing, for instance, a special heat exchanger for the oxygen with two partial heat exchangers mounted in series, the oxygen will issue from the coldest of these heat exchangers for entering in the other at a temperature so much the more lower as the exchange surface of the first will be smaller relatively to that of the second, this temperature can therefore be chosen at will by a suitable choice of the exchange surface.

By interposing the carbon vessel in the path of the oxygen between the heat exchangers, the carbon will thus be subjected to the desired temperature.

As there is no inconvenience, but actually advantages, in operating at a very low temperature, it is thus possible to dispense with a special heat exchanger in oxygen apparatus which, as in those of Claude, comprise a liquefying device where this oxygen begins to heat up. The oxygen will then be directly admitted in the carbon vessel as it issues from the liquefying device. It can be even allowed to come in contact with carbon when issuing from the vaporizer.

Thus nothing will be changed in oxygen apparatus, besides the adjunction of the car-

bon vessel which can be arranged, if desired, in the heat preserving mass of the apparatus. Of course, and this is particularly interesting in the case of operations of short duration, it is advantageous not to neglect the liquid residue from the evaporation of the oxygen, which remains in the oxygen apparatus at the end of the operation and which necessarily contains relatively large quantities of krypton and particularly of xenon. For that purpose, the residue may, if necessary, be vaporized in a special vessel and the products of vaporization directed in a carbon vessel answering to the above conditions.

What I claim as my invention and desire to secure by Letters Patent is:

1. The process of extracting krypton and xenon from liquefied oxygen containing the same which comprises evaporating said liquefied oxygen and passing the vapors formed by the evaporation into contact with gas absorbing substances.

2. In the process of claim 1, the step which comprises maintaining the absorbing substances at a low temperature by means of a cold stream of gaseous oxygen produced in the process.

3. The process of extracting krypton and xenon from liquefied oxygen containing the same which comprises evaporating said liquefied oxygen, passing the vapors formed by the evaporation into contact with gas absorbing substances and recovering further quantities of krypton and xenon from the residue from the evaporation of the liquefied oxygen.

In testimony whereof I have signed my name to this specification.

AUGUSTE JULES ADRIEN BLARINGHEM.
